CLOCK CASING

Milton F. Klein, Glens Falls, N.Y., assignor to General Time Corporation, Stamford, Conn., a corporation of Delaware

Filed May 7, 1968, Ser. No. 11,824

Term of patent 14 years

U.S. Cl. D42—7
Int. Cl. D10—01

FIG. 1 is a perspective view of a clock casing showing my new design, the surface shading indicating a material having the appearance of wood;

FIG. 2 is a front elevational view; and
FIG. 3 is a right side elevational view.

The broken line showings of a clock face and hands are for illustrative purposes only.

The rear, not shown, is plain and unornamented.

I claim:
The ornamental design for a clock casing, substantially as shown and described.
